W. W. WAIT, OF RICHMOND, INDIANA.

Letters Patent No. 88,241, dated March 23, 1869.

IMPROVEMENT IN FANNING-MILL.

The Schedule referred to in these Letters Patent and making part of the same.

To all whom it may concern:

Be it known that I, W. W. WAIT, of the city of Richmond, and State of Indiana, have invented new and useful Improvements in Fanning-Mills; and I do hereby declare that the following is a full and exact description thereof, reference being had to the accompanying drawings, making a part of this specification, in which—

Figure 1 is a transverse section,

Figure 2, a longitudinal section, and

Figure 3, a plan view of the shoe.

The same letters in the different figures relate to corresponding parts of the mill.

My invention comprises three particulars in the construction of fanning-mills, one of which consists in the arrangement and operation of a jarring-lever by which the lower screen of the mill receives a motion at its lower end independently of the motion of the shoe. A second improvement relates to an eccentric situated on the fan-shaft, from which the shoe receives one of its motions. The other improvement relates to a peculiar construction of a grain-board, over which the grain flows from the hopper to the screens.

To enable others skilled in the art to make and use my invention, I will proceed to describe the same with reference to the drawings.

The peculiarity of the lever *a*, fig. 1, as applied to fanning-mills, consists in its operation on a fulcrum-pin, and in the manner of changing the fulcrum, so that the lowest point in the stroke of the jarring-end of the lever will be the same when the fulcrum is at different points along the lever, by means of which the screen is always in contact with said lever, and knocking together of the two is thus prevented.

The lever *a* is attached to the cross-piece *D* by means of the fulcrum-pin *C*, and receives its motion obliquely, and at right angles to the lower screen, from the rod *d*.

The latter is operated by a crank, *b*, on the end of the fan-shaft.

The rod *d*, and the rod by which the bell-crank is operated, are both attached to crank *b* on the same wrist-pin.

The lever *a* is provided with holes at intervals along a portion of its length, for the reception of pin *C*; and the holes for a corresponding purpose in the cross-piece *D* are arranged on a parallel line to lever *a*, when the latter is in a position with the end beneath the screen at its lowest point. Thus the motion of that end of the lever is always from a given point upward.

r is a plate supporting pin *C*, which plate is held by another pin, for the accommodation of which latter, a row of holes is provided in cross-piece *D*, parallel to the holes for pin *C*.

g represents the lower screen, the lower end of which rests on the end of the upright section of lever *a*, and extends over the board *F*, by which the grain is carried down and discharged in front of the mill.

The upper end of screen *g* is supported on pivots

attached to its sides, and resting in notched plates *t* at each side of the shoe. Said screen thus has the combined motions of the shoe and of the lever *a* imparted to it.

b represents the eccentric situated on the fan-shaft *J*, by which the rod *c*, shown in fig. 2, is actuated.

The latter has a bearing, *n*, attached to the side of the mill, on the inside, in which it slides, and is connected with the shoe by means of a link, *e*, attached to said shoe in a flexible manner. The shoe is suspended at the rear by rods in the usual manner.

Its front end is supported by an arm, *u*, shown figs. 2 and 3, having a slotted plate, *s*, at its end, which latter is pivoted on a pin inserted vertically through cross-piece *B*, the plate *s* being held in a mortise on the under side of said cross-piece.

The shoe is thus susceptible of a circular motion, which is imparted to it by the combined action of the bell-crank and eccentric *b*, the former of which operates as in ordinary mills, and tends to shake the shoe in a transverse direction, while the action of the eccentric is in a longitudinal direction.

I, shown in figs. 2 and 3, represents the improved grain-board for use in further cleaning after the chaff has been separated from the grain, which is held in the upper grooves of the shoe, and over which the grain passes from the hopper to the screens.

My improvement in said board consists in forming divergent channels, as shown in fig. 3, by means of partition-strips *t*, *t*, &c., on which latter is another, narrower board *I*, shown in fig. 2, the purpose of said improvement being to regulate and prevent an excessive quantity of grain from passing over said board, and, by means of the diverging channels, to deliver the grain evenly to the screens.

When the mill is used for separating the chaff from the grain, board *I* is reversed, with its under side (which is plain,) upward.

Having thus fully described my said invention,

What I claim, and desire to secure by Letters Patent, is—

1. The lever *a*, operating on a fulcrum-pin, and so arranged that the latter may be changed to different points for the purpose of increasing or diminishing the action of said lever on the screen, without changing the lowest point in the lever's motion, substantially as set forth.

2. The eccentric *b* on the fan-shaft *J*, and rods *c* and *e*, for the purpose of giving an end shake to the shoe, substantially as set forth.

3. The grain-board *I*, provided with the divergent partitions, and the board *I*, as set forth, and for the purpose described.

W. W. WAIT.
